UNITED STATES PATENT OFFICE.

JAMES T. SIBLEY, OF NEW YORK, N. Y.

POCKETKNIFE, ETC.

Application filed November 18, 1922. Serial No. 601,765.

To all whom it may concern:

Be it known that I, JAMES T. SIBLEY, a citizen of the United States, and a resident of the borough of Manhattan, city, county, and State of New York, have invented certain new and useful Improvements in Pocketknives, Etc., of which the following is a specification sufficient to enable those skilled in the art to which the invention appertains 10 to utilize the same.

While applicable to knives of various sizes and kinds generally, having blades foldable into the handles thereof, my improvements are designed more especially for use in connection with pocket knives of the automatic type, so called, in which the blades are protruded and retracted by means positioned within the handles.

The object of my invention is to attain a 20 simple, inexpensive, but effective structure of this character, which may be conveniently manipulated with facility, and in which the blades are automatically and positively locked in open or closed position without direct finger contact therewith, and also in which absolute safety is attained in that the blades cannot accidentally protrude when the knife is closed, and are held rigid when extended for use. To this end the invention 30 consists in the specific construction, combination and arrangement of parts described and claimed, distinctive features relating to the blade advancing, retracting and locking mechanism, all as hereinafter fully set forth.

In the accompanying drawings, I exemplify a practical embodiment of the essential features of my invention in a two-bladed knife, although I do not limit myself thereto, since a single-bladed knife may be thus 40 equipped, and modifications in minor details resorted to without departing from the spirit and intent of my invention in this respect. Furthermore, the drawings show the structure and component parts thereof 45 on an enlarged scale for convenience of illustration.

With this understanding,

Fig. 1, is an elevation of the front or open edge of the knife, with one blade extended, 50 and both blades broken away in part;

Fig. 2, is a sectional elevation taken upon plane of line 2—2, Fig. 1;

Fig. 3, is a longitudinal sectional elevation taken upon plane of line 3—3, Fig. 2; 55

Fig. 4, is an inner face elevation of what

may be designated as the right side plate of the knife handle;

Fig. 5, is an elevation of the outer face of said right side plate of the handle;

Fig. 6, is an elevation of the inner face 60 of the left side plate of the handle;

Fig. 7, is a view of one of the knives, detached;

Fig. 8, is a perspective view of one of the 65 blade-actuating toggles;

Fig. 9, is a cross section taken upon the planes of the line 9—9, Fig. 5;

Fig. 10, is a perspective view of the right slide plate;

Fig. 11, is a like view of the left slide 70 plate;

Fig. 12, is a view illustrating function of the blade actuating toggles.

The handle H, of my knife consists essentially of the right side cheek plate h', and 75 the left side cheek plate h'', both rigidly attached to the spine h, the thickness of which latter prescribes the width of the blade channel C.

I herein show and describe the installation of two knife blades B', B'', within the handle H, although said handle H, may be provided with only a single blade, if so desired, with but slight change of structure, 80 as hereinafter set forth.

The side or cheek plates h', h'', of the handle are not only spaced and held apart by the spine h, but also by the fulcums f, f, constituting the medial portions of the screw bolts f', f'', said medial fulcrum portions f, f, being of greater diameter than the other portions of the bolts f', f'', so as to form bearing shoulders for the opposed inner surfaces of the side plates h', h'', of the handle H, as shown more particularly in 90 Fig. 3, of the drawings. The threaded ends of the bolts f', f'', engage with nuts f'', f'', countersunk in one of the side plates of the handle, as also shown clearly in said Fig. 3.

The shank or tang b, of each knife blade 100 B, is formed with an elongate slot b*, extending in parallel alignment with the blade, the side walls of which slot b*, straddle a fulcrum f, while admitting of a prescribed degree of movement and play of said blade, 105 as and for the purpose hereinafter set forth.

The tang b, of each blade B, is also formed for pivotal connection with one extremity of a toggle T, the other extremity of which toggle is pivotally connected with 110

a slide S' , S^2 , fitting within a recess in the inner face of one of the side pieces of the handle. Thus, where the handle H , is provided with two blades B' , B^2 , as shown in the accompanying drawings, the toggle T , of one blade B' , is pivotally connected with the arm s' , of the slide S' , while the toggle T , of the other blade B^2 , is pivotally connected with the arm s^2 , of the other slide S^2 .

10 The body plate of the slide S' , is slidably positioned in the recess h'' , formed for the purpose in the inner face of the handle cheek piece h' , while the body plate of the other slide S^2 , is correspondingly slidably positioned in a recess h^{22} , formed for the purpose in the inner face of the handle cheek piece h^2 , as will be seen by reference more particularly to Fig. 3, of the drawings. The main difference between the two slides S' , S^2 , is that S' , is formed with a spring arm s^x , for contactual engagement with the body plate of the other slide S^2 , thereby holding both slide body plates apart and against the rear walls of their respective recesses h'' , h^{22} , by elastic resilient pressure, which does not, however, prevent their being forcibly slid longitudinally in either direction within said recesses by means of the finger studs s'' , s^{22} , which protrude through longitudinal slots h^{13} , h^{23} , formed for the purpose in the cheek pieces h' , h^{21} . h^{14} , and h^{24} , are locking abutments by means of which the slides S' , S^2 , may be held in advanced or retracted positions.

20 They are situated within the recesses h'' , h^{22} , but are of less thickness than the depth of said recesses, as will be seen by reference to Fig. 9, which, it will be remembered, is a cross section upon the planes of zig-zag line 9—9, Fig. 5, so taken as to show both of said locking shoulders in section. The difference between the depths of the recesses h'' , h^{22} , and the protrusion of the locking abutments h^{14} , h^{24} , therein, is sufficient to admit of the movement of the slides S' , S^2 , past said locking abutments h^{14} , h^{24} , when the said slides are pressed inward by means of the finger studs s'' , s^{22} , against the resistance of the spring arm s^x , which tends constantly to hold said slides against the rear walls of their respective recesses h'' , h^{22} , as indicated more particularly in Figs. 1 and 3, of the drawings. The slides S' , S^2 , are formed with shoulders for engagement

30 with said locking abutments h^{14} , h^{24} , when in either advanced or retracted positions. Thus the slide S'' , is formed with a shoulder s^{12} , for holding the slide in retracted position (as in Fig. 2) and with a shoulder S^{13} , for sustaining the slide in advanced position, (as in Fig. 10).

40 The tang or shank b , of each blade is formed with a rearwardly projection tongue b' , for engagement, when the blade is in

50 extended position, with a sustaining shoul-

der h^x , on the end of the spine h , as shown in Fig. 2, thereby holding the blade rigidly during use.

The operation is as follows: The blades being in closed positions within the hollow handle, the blade required is opened up and advanced by means of the finger stud attached to the slide involved. Thus, by way of illustration, and with the understanding that the modus operandi is essentially the same in the case of either blade, we will assume that blade B' , is closed and is required for use, in which case the finger stud s'' , is pressed inward so as to enable the slide S' , to clear the locking abutment h^{14} , and said slide S' , is then pushed backward, causing the toggle T , to rock the blade B' , on its fulcrum f , as illustrated in Fig. 12. The continued backward movement of the slide S' , rocks the blade B' , into the position indicated by dotted lines in said Fig. 12, and the completion of the movement when the stud s'' , contacts with the rear end wall of the slot h^{13} , as in Fig. 3, retracts the blade B' , sufficiently to allow the tongue b , on its tang b , to engage with the sustaining shoulder h^x , on that end of the spine h , as shown in Fig. 2—the tang slot b^x , admitting of this retractile movement. In this position the shoulder s^{12} , of the slide S' , automatically engages with the rear end of the locking abutment h^{14} , when the stud s'' , is released, thereby allowing the spring s^x , to reassert itself and force the slide back against the rear wall of the recess h'' . In closing the blade the operation is reversed, the slide S' , being pressed inward to clear the abutment h^{14} , and then moved forward, causing the toggle T , to return the blade B' , to its normal position within the handle H , the release of the finger stud s'' , allowing the slide to resume its position against the back wall of the recess h'' , with its shoulder s^{13} , in contactual engagement with the locking abutment h^{14} .

It is to be noted in this connection that the spring s^x , by bearing against the body plate of the slide S^2 , functions for both slides, in that it tends constantly to hold both against the rear walls of their recesses h'' , h^{22} , as will be seen more particularly by reference to Fig. 3, of the drawings, affording the essential elastic resilience for this purpose.

It will be seen that by my construction and arrangement of parts, the blade is automatically and positively held and locked in both positions, and can only be released by manipulation effected by means of the finger stud, which is sustained in normal position by elastic resilient pressure.

In order to provide for the replacement of blades when desired, I prefer to form the tangs thereof with pivotal studs b^2 , b^2 , and to form the toggles T , of bendable sheet metal

with pivotal holes t , t , for engagement with said studs b^2 , b^2 , on the tang of the blade, so that by spreading the sides of the toggle T , apart slightly the blade may be disengaged therefrom and a new one substituted,—the sides of the toggle being again bent inward to engage the pivotal studs b^2 , b^2 , on the new blade. For this reason one or both of the handle cheek pieces h' , h^2 , are preferably secured to the spine h , of the handle by means of nuts f' f' , as indicated more particularly in Fig. 3, so that the toggles and other operative parts of the knife are rendered accessible upon occasion.

15 What I claim as my invention and desire to secure by Letters Patent is,

1. In a knife of the character designated, the combination of a blade, the tang of which is formed with an elongate fulcrum slot and 20 with a locking tongue, a fulcrum on the handle extending through said elongate slot in the tang of the blade, a toggle pivotally connecting the tang of said blade with a slide mounted in a recess in the handle, elastic 25 resilient pressure means tending constantly to hold said slide against the back wall of said recess, said slide formed with shoulders for contactual engagement with a locking abutment in the handle and with a finger stud, and said handle formed with a locking abutment and with an elongate slot through which said finger stud protrudes, and also with a shoulder for engagement with said locking tongue on the tang of the 30 blade, substantially in the manner and for the purpose described.

2. In a knife of the character designated, the combination of two blades, the tang of each of which is formed with an elongate 40 fulcrum slot and with a locking tongue, fulcrums on the handle extending through said elongate slots in the tangs of the blades, toggles pivotally connecting the tangs of said blades with slides mounted in recesses in the 45 handle, elastic resilient pressure means tending constantly to hold said slides against the back walls of said recesses, said slides formed each with shoulders for contactual engagement with locking abutments on the handle and each with a finger stud, and said handle formed with locking abutments and with elongate slots through which the finger 50 studs protrude, and also with shoulders for engagement with said locking tongues on the tangs of the blades, substantially in the manner and for the purpose described.

3. In a knife of the character designated, the combination of a blade, the tang of which is formed with an elongate fulcrum 60 slot, with a locking tongue, and also with pivotal studs, a fulcrum on the handle ex-

tending through said elongate slot in the tang of the blade, a sheet metal toggle pivotally connecting the tang of said blade with a slide mounted in a recess in the handle and formed with holes for engagement with said pivotal studs on the tang of the blade, elastic resilient pressure means tending constantly to hold said slide against the back wall of said recess, said slide formed with 65 shoulders for contactual engagement with a locking abutment in the handle and with a finger stud, and said handle formed with a locking abutment and with an elongate slot through which said finger stud protrudes, and also with a shoulder for engagement with said locking tongue on the tang of the blade, substantially in the manner and for the purpose described.

4. In a knife of the character designated, the combination of two blades, the tang of each of which is formed with an elongate fulcrum slot and with a locking tongue, fulcrums on the handle extending through said elongate slots in the tangs of the blades, 80 toggles pivotally connecting the tangs of said blades with slides mounted in recesses in the handle, elastic resilient pressure means tending constantly to hold said slides against the back walls of said recesses, said slides formed each with shoulders for contactual engagement with locking abutments on the handle and each with a finger stud, one of said slides being formed with a spring arm bearing against the other slide, and said handle formed with locking abutments and with elongate slots through which the finger 85 studs protrude, and also with shoulders for engagement with said locking tongues on the tangs of the blades, substantially in the manner and for the purpose described.

5. In a knife of the character designated, the combination of a blade the tang of which is formed with an elongate fulcrum slot, with a locking tongue, and also with pivotal 100 studs, a fulcrum on the handle extending through said elongate slot in the tang of the blade, a toggle pivotally connecting the tang of said blade with a slide mounted in a recess in a side plate of the handle and formed with holes for engagement with said pivotal studs on the tang of the blade, pressure means tending constantly to hold said slide against the back wall of said recess, a handle cheek piece, and screws detachably 105 securing said cheek piece to the spine of the handle substantially in the manner and for the purpose described.
